HANDLE FOR KITCHEN TOOLS OR SIMILAR ARTICLES

James L. Hvale and Richard S. Latham, Chicago, Ill., assignors to Ekco Products Company, Chicago, Ill., a corporation of Delaware

Filed July 3, 1961, Ser. No. 65,787

Term of patent 14 years

(Cl. D44—29)

FIG. 1 is a front elevation of a handle for kitchen tools or similar articles showing our new design.

FIG. 2 is an elevational view of the handle as it appears when viewed from the right hand side of FIG. 1.

FIG. 3 is a rear elevational view thereof.

FIG. 4 is an elevational view as it appears when viewed from the left hand side of FIG. 1.

FIG. 5 is an end elevational view taken in the direction of arrows 5—5 as shown in FIG. 1.

FIG. 6 is a section taken along line 6—6 of FIG. 1.

FIG. 7 is a rear end view as it appears when viewed in the direction of the arrows 7—7 in FIG. 3.

We claim:

The ornamental design for a handle for kitchen tools or similar articles, as shown.
